UNITED STATES PATENT OFFICE.

JOHN A. WALKUP AND CHARLES W. WALKUP, OF WACO, TEXAS.

WATER-FEEDING DEVICE.

1,101,363.

Specification of Letters Patent. Patented June 23, 1914.

Original application filed May 10, 1911, Serial No. 626,171. Divided and this application filed June 20, 1912. Serial No. 704,823.

To all whom it may concern:

Be it known that we, JOHN A. WALKUP and CHARLES W. WALKUP, citizens of the United States, residing in Waco, Texas, have 5 invented certain Improvements in Water-Feeding Devices, (being a division of application filed May 10, 1911, Serial No. 626,171, now Patent No. 1,030,693, dated June 25, 1912,) of which the following is a specification.

One object of our invention is to provide a novel form of container or reservoir which shall include conveniently operative means whereby it shall be possible to adjust the 15 rate of discharge of liquid; the arrangement of parts being such that the device shall be inexpensive to manufacture, compact in form and convenient to use.

We also desire to provide a novel and 20 relatively simple adjustable barometric liquid feeding device whose adjusting means shall be capable of accurate regulation to vary the amount of liquid discharged in a given time.

25 These objects we attain as hereinafter set forth, reference being had to the accompanying drawings, in which,

Figure 1 is a front elevation of our liquid feeding device, and, Fig. 2 is a vertical section of the feeding device taken on the line a—a Fig. 1.

In the above drawings, 1 represents a tray or other form of container or body to which it is desired that liquid shall be gradually 35 fed, and in this is mounted the barometric liquid feeding container 2, consisting of a metallic or other vessel having the lower half of one of its sides bent or extended inwardly as indicated at 3, and cut off so as 40 to terminate a short distance from and substantially parallel with its lower side or bottom in a sealing edge. Adjacent the front edge of the bottom 4, we mount an adjustable set screw 5 whereby the container 45 2 may, within certain limits, be tilted on its rear edge or corner 6, so that its front or liquid discharging edge 7 may be raised to a level immediately adjacent or, if desired, above a horizontal plane through the sealing 50 edge 8 of the inwardly bent side 3.

Under conditions of use the container 2 may be filled with the desired liquid, for example, water, and after the set screw 5 has been sufficiently extended, said container 55 is placed in the tray 1 in the position shown

in the drawing. The outflow of liquid is then prevented since the line of the sealing edge 8 is below the horizontal plane extending through the liquid discharging edge 7, and the entrance of air to the container is 60 effectually prevented. Thereafter by turning the set screw 5, the liquid discharging edge 7 may be lowered until finally it is slightly below the horizontal plane of the sealing edge 8, whereupon a small quantity 65 of air is permitted to pass below said edge. A corresponding quantity of liquid in the container 2 is thus permitted to flow out over the edge 7 into the tray or other receptacle and this flow is substantially continuous, the 70 amount discharged depending upon the adjustment of the set screw.

It will be noted that with the arrangement of parts shown, there is always a body of liquid exposed between the sealing and 75 water discharging edges so that if desired, the device may be used as a fountain independently of the tray.

We claim:

1. The combination of a container having 80 an inwardly extended side terminating in an edge spaced away from the adjacent bottom portion thereof; said bottom portion having an edge extending to a level above that of said edge of the side; with a screw mounted 85 in said bottom portion for adjusting the height of the former edge relatively to that of the latter edge.

2. A liquid feeding device consisting of a liquid containing vessel having a straight 90 discharging edge and also having a rigidly connected portion terminating in a sealing edge; with means for adjusting the position of the container to vary the distance of the liquid discharging edge from a horizontal 95 plane passing through the sealing edge.

3. A barometric liquid feeding device consisting of a reservoir having an internal edge normally sealed against the admission of air; and a screw mounted to partially 130 support said reservoir, the same being adjustable to vary the rate of discharge of liquid therefrom.

4. A liquid feeding device consisting of a container in the form of a box having an inwardly extended side terminating in an edge spaced away from the bottom thereof; with a flow adjusting device in the form of means for varying the angle of said bottom to the horizontal. 105

5. The combination of a barometric feeding device in the form of a reservoir having a water discharging edge and a sealing edge; with means for adjusting said reservoir to 5 simultaneously vary the relative levels of said two edges and thereby vary the rate of discharge of liquid therefrom.

6. The combination in a liquid feeding device of a supporting structure; an elongated reservoir having a bottom portion resting on said structure and provided with a substantially level liquid discharging edge; and an adjustable screw mounted in said bottom portion and serving to par-

tially support the reservoir; the side of said 15 reservoir adjacent the liquid discharging edge being extended inwardly and terminating in a sealing edge spaced away from said bottom portion.

In testimony whereof, we have signed our 20 names to this specification, in the presence of two subscribing witnesses.

JOHN A. WALKUP.

CHARLES W. WALKUP.
